MULTIPLE STATION BLOCK MACHINE
Frank L. Culver, 3811 67th St., Des Moines, Iowa
Filed Dec. 2, 1953, Ser. No. 395,691
11 Claims. (Cl. 25—41)

This invention is a dual mix block machine in which one or more complete building units are made during each cycle of the machine.

In the past many attempts have been made to produce economical building units to simulate quarried products. Each of these various types of methods or machines were plagued by one or more of the following troubles, which ultimately were grave enough to result in failure of the device or product to ever attain and hold nationwide distribution and acceptance. The more serious deficiencies and shortcomings were:

Machine would make only one size and one face relief at a time resulting in very obvious and undesirable unit repetition in the wall.

Machine not capable of proper facing compaction which resulted in a low quality product and great sales resistance.

Low production due to all operations being done at one position resulting in economic infeasibility.

Curing blocks on expensive contoured moulds, thereby limiting production and defeating prime object which was to produce a low priced attractive building unit.

In those units which make a blended product (one having a variety of unit heights, lengths, and face reliefs) the inability to readily or economically change blend to relieve monotony or sameness of every wall.

Excessive size of machine requiring large factory space for it and compaction equipment thereby defeating product economy.

Machines of a nature to require large operating crew, making for high labor costs and making limited operation impractical.

In contrast to the prior art, my invention overcomes above listed deficiencies by its many unique features which permit my invention to fulfill the following objects:

It is an object of this invention to provide a machine which will produce, inexpensively, dual mix building blocks.

It is another object of this invention to provide a machine which will automatically produce building blocks with a variety of face reliefs and blocks varying in length without any time delay or cessation in production.

It is still another object of this invention to provide a machine which, with adjustments and some accessory changes, will produce a second, third, or fourth variety of building blocks composed of a multiplicity of sizes and face reliefs.

It is a further object of this invention to provide a machine to produce a block with its face compacted to any desired density.

It is a further object of this invention to provide a machine to produce a block having an attractive face uncontaminated by residue from previous cycles of machine operation.

It is a still further object of this invention to have product rest on a plain inexpensive pallet while curing.

It is still a further object of this invention to provide a machine which will meter the separate mixes automatically in the proper amounts and place them in the correct mould compartment at the right time according to a predetermined cycle.

It is another object of this invention to provide a machine which will complete many of the functions of dual mix block making within itself, thereby keeping accessory equipment at a minimum.

It is still another object of this invention to provide

2

a machine to produce dual mix blocks while occupying a minimum of factory space.

It is a further object of this invention to provide a machine which is capable of accomplishing above objects 5 economically with a single operator.

FIGURE 1 is a horizontal section of a plan view of block machine taken on line 1—1 of FIGURE 13 showing stations A through F.

FIGURE 2 is a pictorial view of mold with one of corner molds in position to be engaged with face mold.

FIGURE 3 is a pictorial view of one of jamb molds which is used in place of corner molds when making window or door jamb blocks.

FIGURE 15 is a vertical section taken on line 15—15 40 of FIGURE 5 and,

FIGURE 16 is a vertical section taken on line 16—16 of FIGURE 5.

For purposes of illustration, I have shown a machine having six stations designated by the letters A, B, C, D, E, and F. Station A is for the automatic feed and compaction of face mix. Station B is for applying and compacting extra facing mix used when corner or jamb blocks (those having two or three outside faces which will be exposed when laid in the wall) are made. Station C is for feeding, compacting, and finishing of back up portion of block. These are generally referred to herein as the compacting stations and as such have auxiliary supports immediately beneath them to transfer force of compactor to base below.

BASE, FRAME, AND MOVABLE ELEMENT DESCRIPTION

As illustrated in FIGURE 1, the machine is supported on base identified by the numeral 20, and has the various parts integrated by a frame 22. Bearing 24 is rigidly mounted on base 20. Bearing 25 is rigidly attached to 55 frame 22. The movable element generally designated 26 is composed of a shaft 28 journaled in bearings 24 and 25, a hub 30 and a drum 32 rigidly secured to shaft 28, a set of arms 34 attached to hub 30, a plate 36 attached to arms 34 and drum 32. A set of latches 38 are mounted on arms 34, a set of mold plate supports 40 secured to arms 34, and a set of mold plates 42 attached to mold plate support 40 by cap screws 44, best shown in FIGURES 13 and 16. As movable element 26 indexes to the several stations later described, mold plate supports 40 come to rest lightly on wear plates 41, which are mounted to impact supports 43, which in turn are rigidly attached to base 20 at the several compacting sta-

tions as clearly shown in FIGURE 5. Mold side switch 45 is mounted to impact support 43 as shown in FIGURE 5. Mold 46 is removably positioned on mold plate 42 as illustrated in FIGURE 16. In FIGURE 5, lugs 47 are securely attached to mold plate 42.

ADJUSTMENTS

In adapting this part of block machine to making blocks of a different height (considering them from the aspect of being laid up in the wall), a separate set of mold plates 42 would be substituted and fastened to machine by screws 44. A separate set of molds would be provided for use on the new set of mold plates 42.

MOLD, SEPARATOR, AND KEY LUG DESCRIPTION

I have shown for purposes of illustration in FIGURE 2, a mold 46 for two blocks, which has integrally cast therein, a recess into which raised portion of mold plate 42 fits, and cast thereon, lower separator 48, the position and number of which on the different molds will vary. To further clarify, a mold having two lower separators would make three blocks, while a mold having no separators would of course make only one block. Each lower separator will have a key lug positioned directly beneath it in the same manner as the one designated 48 has to key lug 50. Corner molds 52, having dowels 56 are removably mounted on mold 46 when in use. In FIGURE 3, a jamb mold 54 is shown with dowels 56 for alternate use with mold 46 when jamb blocks are to be made. Molds as disclosed should be differentiated from ordinary molds in that they are used alternately with each other in any number in every day production without any "down time" or delay due to said alternate use.

AUTOMATIC FACING POSITION DESCRIPTION

Station A

As best illustrated in FIGURE 6, frame 22 supports the facing mix storage hopper 57, which has a false front 58 hingedly mounted therein. Front side of hopper 57 has collar 67 rigidly attached thereto, and pin 69 movably positioned therein and located by use of key 71 in one of the several adjusting holes provided. A conventional type time controller 59 is mounted on hopper 57, below which a facing feed drawer 60 is movably mounted. A shut-off plate 62 is secured to rearward portion of drawer 60, to which is attached piston rod 64, of feed drawer pressure cylinder 66. This cylinder is secured to bracket 68 which is mounted on frame 22. Trip bar 63 is mounted to plate 62 and engages alternately drawer bottom retraction switch 61 attached to hopper 57, and compaction start switch 65 secured to bracket 68. Feed drawer 60 and feed drawer bottom 70 are laterally positioned by guides 72 which are mounted to frame 22. Two racks 74 are attached to drawer bottom 70 and run on gears 78. Drawer bottom is also supported by and rolls on rollers 76. Feed drawer retraction switch 75 is mounted on bracket 68 to engage drawer bottom 70. Gears 78 mounted near the ends of equalizer shaft 80, are rigidly connected thereby. Shaft 80 is journaled in bearings 82 which are mounted to frame 22. Piston rod 84 is secured to feed drawer bottom 70 at its rear central portion, and reciprocates within feed drawer bottom pressure cylinder 86 which is mounted to bracket 68.

VALVE AND CYLINDER COMBINATION

Unless otherwise specified, all cylinders mentioned in this application have incorporated therein as a closely connected part of the cylinder, electrically operated two-way valves of a conventional nature. These valves are not shown as they are conventional units for directing a fluid pressure to the ends of the cylinder to cause

the pistons to extend or retract the piston rods. These conventional valves are of the type wherein an electrical impulse of a very short duration actuates the valve, which then remains in the new position although no electrical circuit is maintained to so hold it. This leaves the valve in a de-energized state and ready to receive the next impulse to reverse its action without resorting to the various relays and complicated electrical circuits.

MOLD SIDES

Upper mold sides 88 are rigidly but detachably secured to frame 22 over mold 46. Lower mold sides 90 are detachably mounted to arms 92, which are pivoted to support lugs 94, and are secured to piston rod 98 of mold sides cylinder 100 by yoke 96. Mold sides cylinder 100 is mounted to frame 22 via plate 102. Feed drawer and drawer bottom advance stroke switch 95 is mounted to frame 22 so as to engage trip bar 97 which is secured to yoke 96.

COMPACTORS

Compactors 104 are removably attached to guide bars 106 which reciprocate in guides 108 which are rigidly mounted in hopper 57. Piston rods 110, secured to bars 106, reciprocate in compactor cylinders 112, which are rigidly attached to hopper 57. Controller 59 is of the conventional type wherein a primary timer determines the duration of the period during which the secondary or oscillating controller functions. The secondary controller emits time spaced signals to two separate circuits activating first the advance portion of two way valves in compactor cylinders 112 and secondly the retraction portion of valves in same cylinders as long as it is energized by primary timer. Secondary oscillating control, when de-energized always comes to, and rests on retraction signal.

ADJUSTMENTS

In adapting automatic facing portion of block machine to making blocks of a different height, a set of proper sized compactors 104 would be attached to guide bars 106. Upper mold sides 88 and lower mold sides 90 of the proper width would be attached to frame 22 and arms 92 by cap screws or other convenient means. Bracket 68 with feed drawer cylinder 66 and drawer bottom cylinder 86 attached would be repositioned on frame 22 by screws or other means in holes provided in frame 22 so that leading edges of drawer 60 and bottom 70 would maintain the same relative position with reference to adjacent edge of upper mold sides 88 which they have as shown in FIGURE 6. Then false hopper front 58 is adjusted by entering key 71 in proper hole in pin 69, and collar 67. An alternate position is illustrated by dashed lines in FIGURE 6 as would be used when making blocks having a lesser height.

OPERATION OF AUTOMATIC FACING OPERATION

Station A

In following the operation of the previously described mechanism at automatic facing operation, an electrical impulse from switch 235 (later to be described) actuates a conventional valve, which is integral with lower mold side cylinder 100 causing normally extended piston rod 98 to retract, carrying with it yoke 96, and arms 92, to drop the lower mold sides 90 into position shown in FIGURE 6 thereby forming a mold compartment having mold 46 for its bottom. As yoke 96 reaches bottom of its travel, trip bar 97 secured thereto actuates feed drawer advance switch 95. The electrical impulse released by operation of switch 95 actuates valves which are incorporated in feed drawer cylinder 66 and feed drawer bottom cylinder 86.

The operation of valves in cylinders 66 and 86 di-

rects fluid pressure into the proper end of cylinders as shown in FIGURE 6 which forces piston rods 64 and 84 to move feed drawer 60 and drawer bottom 70 to a position above the upper mold sides 88. The feed drawer 60 and drawer bottom 70, enclose charge of facing mix dropped by gravity from hopper 57. During period when drawer is extended out over mold 46, shut off plate 62 closes bottom of hopper 57 restraining mix from further feeding or spilling. As feed drawer 60 reaches end of outward stroke, feed drawer bottom retraction switch 61 is operated by bar 63, which actuates the electrically controlled valve in feed drawer bottom cylinder 86 causing piston rod 84 to retract and withdraw drawer bottom 70, thereby dropping facing mix charge through upper mold sides 88, and evenly into mold compartment.

As drawer bottom 70 reaches end of retraction stroke, its trip rod 73 actuates feed drawer retraction switch 75, sending electric impulse to valve in feed drawer cylinder 66 causing fluid pressure to be applied so as to retract piston rod 64 which withdraws feed drawer 60 from extended position over mold 46 and shut off plate 62 from extended position under hopper 57 to starting position as shown in FIGURE 6. This allows a new charge of facing mix to fill feed drawer 60. As feed drawer 60 reaches end of retraction stroke, trip bar 63 engages and activates compaction start switch 65, sending impulse which activates the conventional timed oscillating control 59 causing piston rods 110, guide bars 106, and compactors 104 to oscillate up and down, imparting blows to mix in mold compartment. This thoroughly compacts mix against mold face relief.

Force of compactor blows is transferred thru mold plate support 40 to wear plate 41 and to impact support 43 at this station and thence to base 20. At the same oscillating control 59 terminates period of compactor oscillation, it closes a second set of points which activates valve in lower mold side cylinder 100 which then extends piston rod 98 and raises lower mold sides 90, by means of yoke 96 and arms 92. Mold 46 with compacted facing thereon now is clear of all mold sides and ready to be indexed to following position. Mechanism at station A now remains idle until after indexing is completed, whereupon cycle repeats itself. It will be noted as illustrated in FIGURE 7, that compactors 104, shown in down position, are so spaced as to clear lower separators 48, regardless at which division point that they may be positioned or, of the number of them used on any one mold.

INDEXING MECHANISM DESCRIPTION

Drum 32 has already been set forth due to its rigid connection with element 26. In FIGURE 14, indexing pressure cylinder 224, being pivotally mounted to frame 22, has a piston rod 226 operably mounted within it, the outer end of which is pivotally attached to flanged bearing 228. As illustrated in FIGURE 13, bearing 228 is rotatably positioned about shaft 28 and removably attached to clutch 230 which is suspended from flanged bearing 228 in a concentric position about drum 32. Clutch 230 is connected by conduit 232 to valve 234 which is connected to source of fluid pressure. Piston rod 226, as shown in FIGURE 14, is also rigidly connected to cam 227 which engages roller 229 of valve 231. Valve 231 is connected to outside source of fluid pressure by conduits 237 and is mounted on cylinder 224 and connected thereto at each end by conduits 233. Switch 235 is attached to indexing cylinder 224 in an operable manner to engage cam 227 and becomes the station cycle start or trigger switch to activate all following operations at the various stations which begin immediately after indexing is completed.

This switch is used rather than one actuated by final latching action, in anticipation of this later action being performed, and safely so, since adjustments on stroke of piston rod 226 will accurately regulate movement and

stopping point of element 26. This anticipation, along with others to follow is an important and valuable phase of this invention due to the time saving resulting therefrom. As an example, let us estimate the total time saved by "anticipation" to be two seconds. This in relation to the total operating time cycle, which has been calculated at eighteen seconds, becomes conservatively 10% of the total cycle time. This means that in any one day, production would be increased by approximately 10% by the use of anticipatory signals. This extra production with no increased labor costs could be the difference between operating at a profit or a loss during times when product's market may be vigorously competed for.

Best shown in FIGURE 1, indexing latch cylinder 236 is mounted to frame 22 between guides 242. Piston rod 238, operably mounted to reciprocate within indexing latch cylinder 236, is securely connected to indexing latch seat 240, which reciprocates within and is guided by latch seat guides 242, which are rigidly attached to frame 22. Latch cylinder 236 and latch guides 242 are so positioned on frame 22 that latch seat 240 will engage latch dog 38 when mold plate 42 is accurately positioned at one of stations. In FIGURE 5, indexing switch 165 is mounted on frame 22.

25

INDEXING MECHANISM OPERATION

In following sequence of operation, operator depresses button on indexing switch 165, which sends electrical impulse which actuates integral valves in latch and indexing cylinders 224 and 236. Pressure reversal in latch cylinder 236 causes rod 238 and latch seat 240 to retract, thereby disengaging latch dog 38. Pressure reversal in indexing cylinder 224 causes rod 226 to retract carrying cam 227 back with it. As cam 227 moves, roller 229 is allowed to move, opening valve 231 which allows greater flow and therefore a faster piston and rod travel rate. As some point along the travel of rod 226 is reached, roller 229 begins ascent which results in throttling action in valve and the resultant deceleration of piston rod 226. Since end of rod 226 is connected to flanged bearing 228 and clutch 230, its movement causes element 26 to rotate. The cam and valve action described above imparts to that rotation, a slow smooth start, a regular uniform acceleration, a fast intermediate travel rate, a regular uniform deceleration, and a slow smooth stop, necessary as face mix sides are unsupported.

As rod 226 reaches end of travel, outer end of cam 227 engages station cycle starting switch 235, which then sends electric signals to valves in cylinders 100, 116, 150, 214, 236, and clutch valve 234, and to sounding gong (not shown) with actions as follows; lower mold side cylinder 100 retracts rod 98, which forms mold compartment with mold 46 and starts automatic facing mechanism on its cycle of operations, cylinders 116, 150, and 214 start actions which will be described later in connection with the operations to which they belong. Latch cylinder 236 extends rod 238 and latch seat 240 to engage latch dog 38 for final positioning and locking of movable element 26. Clutch valve 234 is reversed, allowing pressure medium to leave clutch 230, thereby disengaging itself. Gong or signal of any convenient type advises operator it is time to bear in next pallet for production of next blocks.

65

CORNER OR JAMB FACING MECHANISM DESCRIPTION

Station B

In FIGURE 9, rear mold side support bracket 114, onto which are pivotally attached rear mold side cylinder 116 and rigidly mounted bearings 118, is adjustably mounted to portion of frame 22. Mounted to operate with rear mold side cylinder 116 is piston rod 120, having its outer end hingedly connected to inner end of yoke type bellcrank 122. Rear mold side 124 has its position movably restricted by being attached through bearings

118 to outer end of bellcrank 122, links 126, and bearings 118 to bracket 114.

Front mold side 128 is operably attached thru guides 130, to positioner bars 132, which are movably held in place by threaded rods 134, having threaded sprockets 136 screwed thereon, and vested in retaining brackets 138. Handle 133 is rigidly attached to adjusting sprocket 135, which, with its integral shaft is journaled in bearing bracket 137, the latter being rigidly but adjustably mounted to impact support 43. Chain 139 encompasses sprockets 135 and 136.

As shown in FIGURE 1, corner mold restraining arms 140 are pivotally mounted on front mold side 128 and operably attached to restraining arm cylinder 142 by trunnion type mounting and to piston rod 144 by yoke 146. By this coupling method, the full piston rod stroke pivots both arms 140 to their greatest movement about their pivots. Mold side retraction switch 147 is operably mounted to restraining arm cylinder 142 to operably engage yoke 146. Piston rod 148 is rigidly attached to front mold side 128 and operably mounted to front mold side cylinder 150 which rests on movable base 152 which is rigidly connected to positioner bars 132. Restraining arm switch 151 is operably mounted on the impact support 43, to engage lug 153 on guides 130. In FIGURE 1, mold side switch 155 is mounted to frame 22.

ADJUSTMENTS

In making blocks of other heights rear mold side support bracket 114 would be repositioned by loosening fasteners and moving outward or inward as the change may dictate, and then retightening again to mating portion of frame 22 as shown in FIGURES 1 and 9. Front mold side 128 is repositioned correctly to mold by turning handle 133 which moves sprocket 135 and chain 139. This rotates all four sprockets 136 in unison and causes all four threaded rods 134 to be extended outward or withdrawn inward whichever may be required. In FIGURE 12 restraining arm adaptor 141 is shown secured in place on restraining arm 140 which effectively narrows the "grip" and permits the locking of mold sides 124 and 128 together in the same manner as shown in FIGURE 1.

OPERATION OF CORNER OF JAMB FACING MECHANISM

Station B

At station B, the operator places the corner or jamb molds 52 or 54 in place by resting the bottom of them on mold plate 42 and sliding them toward mold 46 until dowels 56 have engaged holes provided. Operator then pushes "close" portion of mold side switch 155 as shown in FIGURE 1. This actuates integral valve in rear mold side cylinder 116, causing piston rod 120 to extend, rotating bellcrank 122 in journals 118 which forces rear mold side 124 to approach mold 46, all the while rear mold side 124 being held in vertical plane by links 126 turning about bearings 118.

During this period, piston rod 148 is also extending and elevating front mold side 128 into position beside mold 46 and engaging mold restraining arm switch 151 with lug 153; it, rod 148 having been energized also by switch 155. This restraining arm switch 151 energizes integral valve in restraining arm cylinder 142 causing piston rod 144 to extend and restraining arms 140 to pivot, thereby supporting corner molds 52, and locking mold sides 124 and 128 together as shown in FIGURE 1. FIGURE 12 also shows restraining arm 140 holding mold sides 124 and 128 in place as well as the use of restraining arm adaptor 141 as used when making narrower blocks.

Operator then places additional facing mix into ends of mold compartment and compacts it with any suitable means such as a conventional bench rammer (not shown). After compaction is completed, operator pushes open button of mold side control switch 155 which ac-

tivates integral valve in restraining arm cylinder 142 causing piston rod 144 to retract which unlocks mold sides 124 and 128 and returns arms 140 to open position as shown by dotted lines in FIGURE 1. This causes yoke 146 to engage front and rear mold side retraction switch 147 sending impulse to integral valves in mold side cylinders 116 and 150 effecting the retraction of piston rods 120 and 148, thereby withdrawing mold sides 124 and 128 from mold 46 and mold corners 52.

10 This leaves mold, mold corners, and compacted facing free and ready to move to following station C at next indexing of machine. When regular blocks (those without facing on the ends) are being produced, station B is idle, with compacted facing and mold remaining status quo for one machine cycle. After which, mold and facing proceed to following station for product completion.

"BEAR-OFF" DESCRIPTION

Station C

Although the actual "bear-off" operation follows the "back-up" process, the mechanism is described at this time since the "bear-in" function takes place prior to the "back-up" process and uses the mechanism herein described as "bear-off." It is so called since its most important function is "bear-off."

In FIGURE 1, left bear-off support 154L is pivotally mounted to frame 22, by journals 156, and rests on treadle 157L shown in FIGURE 5. Treadle 157L is pivotally mounted to base 20 by pin 159. Right bear-off support 154R is of identical structure but opposite hand and is similarly mounted. Left bear-off roll over cradle 158L having bear-off fingers 160L rigidly mounted thereon is pivotally mounted to support 154L and has position where pallet 164 may, in a vertical plane, loosely rest. When roll over cradle 158L has been rolled over as shown by dotted lines in FIGURE 4 pallet 164 then occupies a horizontal position. Cradle 158L has cylindrical lock bars 161 extending from its ends.

"BACK-UP" MECHANISM DESCRIPTION

Station C

CORE CARRIAGE

45 In FIGURE 13, core carriage cylinder 214 is mounted to frame 22 via trunnion 216 and has piston rod 212 reciprocally mounted therein. Adjustable linkage 210 has one end secured to rod 212 and the other pivotally mounted to core carriage 178. Mold side retraction switch 179 is operably mounted to support bracket 176 to engage adjustable trip bar 197 secured to core plate 184. In FIGURES 1 and 11 core carriage 178, having side channels 177, is mounted and guided by them on rollers 218 which are secured to shafts 220 which are journaled in bearings 222 secured to frame 22.

50 Spacer bars 191 are rigidly mounted to side channels 177 and in turn become a rigid support for racks 202 which are securely fastened thereon. Rear mold side 182, having openings therein to receive cores 192 and upper separators 180, and having cylindrical locks 183 on its ends, is rigidly attached to spacer bars 191 to effectively form the front end of core carriage 178. In FIGURE 16, angle bracket 194 is rigidly mounted on rear mold side 182 and carries thereon at least one separator switch 195 operably mounted to engage key lug 50 on mold 46 when core carriage 178 advances thereto. In FIGURE 13, guide bar 186 is rigidly attached to carriage side channels 177 and has openings therein to receive upper separators 180 and core plate cylinder 208. In FIGURE 1, support bracket 176 is adjustably mounted on core carriage 178 by being laterally restrained within clips 175, which are secured to carriage 178, and restricted from moving forward or rearward by cap screw 181 threaded into one of the several holes provided in carriage 178.

CORE PLATE ASSEMBLY

In FIGURE 1, gears 200 roll on rack 202 and are rigidly mounted on shaft 198 which is journaled in bearings 196. Core plate has bearings 196 rigidly attached thereto and therefore rides on racks 202 via gears 200 and shaft 198. Cores 192 and half cores 193 are removably attached to core plate 184 and guided within openings in rear mold side 182. In FIGURE 13, angle plate 204 is rigidly attached to core plate 184 and has piston rod 206 rigidly mounted to it. Rod 206 is reciprocally mounted within core plate cylinder 208 which is nested within opening in guide bar 186 and rigidly mounted to support bracket 176.

UPPER SEPARATOR ASSEMBLY

In FIGURE 1, upper separators 180 are shown nested within rear mold side 182, core plate 184, and guide bar 186, and also attached to piston rods 188, which are reciprocally mounted within separator cylinders 190, which are rigidly mounted to support bracket 176.

FUNNEL STRIKE OFF 166

In FIGURE 13, shield plate 168 is securely attached to rear mold side 182 and guide bar 186 and restrains core plate 184 and upper separators 180 against any upward movement. Side guides 170 are rigidly fastened to shield plate 168. Funnel strike off 166 resting on shield plate 168 and between side guides 170 is rigidly secured to piston rod 172 which is reciprocally mounted within funnel strike off cylinder 174 which is rigidly mounted to bracket 176. Trip bar 171 is mounted to funnel strike off in an operable position too engage finishing plate switch 173 mounted on funnel strike off cylinder 174.

FEEDER 258 AND HOPPER 260

In FIGURE 13, belt feeder 258 is mounted through journals to frame 22 below hopper 260 in the usual manner. Hopper 260 is rigidly mounted to frame 22 and has mounted to it, a feeder motor start switch 261, time controller 263, and an oscillating control 265. Feeder sprocket 262 is driven by chain 264 which is driven by sprocket 266 mounted on gear motor 268 which is adjustably mounted to frame 22.

COMPACTING AND FINISHING

In FIGURE 13, finishing plate assembly 270 is movably mounted in guides 272, which are rigidly attached to frame 22. Plate assembly is suspended over mold 46 by links 274 pivotally mounted to assembly 270 and hopper 260. Links 274 are supported by yoke 276, pivotally mounted thereto, and finishing assembly cylinder 278 also pivotally mounted thereto. Piston rod 280 is mounted to reciprocate within finishing assembly cylinder 278 and is pivotally mounted to frame 22.

In FIGURE 5, finishing plate 282 is rigidly attached to plate assembly 270 and has slots therein to receive compaction bars 284, which are movably mounted within guide plate 286, and connected to piston rods 288. These rods 288, are mounted to reciprocate within compaction bar cylinders 290 which are mounted rigidly to plate assembly 270. Trip plate 289 is attached to assembly 270 in position to engage block thickness switch 291 mounted on guide angle 271, which is attached to guides 272.

MOLD SIDES AND LOCKS

As illustrated in FIGURE 5, filler block 244 is removably secured to mold side 246 by cap screw 248. Mold side 246 is rigidly attached to ram 250 which in its extended position engages lug 47 and is slidably mounted within ways 252. Core advance switch 251 is attached to ways 252 in an operable position to engage trip bar 253 which is secured to ram 250. Ram 250 is directly connected to piston rod 254 which is mounted to reciprocate within mold side cylinder 256 which is rigidly mounted to frame 22. Core carriage retraction switch 273 is operably mounted on mold side cylinder 256 to

engage ram on retraction stroke. In FIGURE 15, mold sides 246 have wing latches 247 which engage cylindrical lock bars 161 and 183 when in the down position.

ADJUSTMENTS AT "BACK UP" STATION C

For making blocks of other heights, the following adjustments are made: adjustable linkage 210 is shortened or lengthened as desired which affects the repositioning of core carriage 178 and rear mold side 182 with reference to new mold 46 to be used. Support bracket 176 is loosened from core carriage 178 and repositioned by entering screw in one of the alternate holes provided. This repositions funnel strike off, upper separators, and cores as all three have their powering devices anchored to bracket 176. It also repositions mold side retraction switch 179 located on bracket 176. Trip bar 197 is adjusted to engage funnel strike off switch 199 according to stroke length. Compactors 284 and finishing plate 282 are then changed for those of correct width. Time controller 263 is reset to indicated position for block height to be made, thereby properly regulating feeding and compaction time. Roll over cradles 158 are exchanged for the ones to fit block height to be made.

BACK UP STATION OPERATION

Station C

BEAR-IN OPERATION

We will assume for a starting point of this operation that machine has indexed and a mold 46 with a set of two corner molds 52 has come to rest at station C with compacted facing in place. Operator has heard the anticipatory gong sounded prior to indexing completion and has readied himself for "bearing-in." At the same time gong sounded, core carriage cylinder became energized by valve movement triggered by station cycle starting switch 235, thereby retracting rod 212 shown in FIGURE 13 and advancing core carriage 178 and rear mold side 182 into operable position with mold 46.

Operator has a pallet 164 in place on roll over cradle 158 in position shown by solid lines in FIGURE 4. He swings these into position, pivoting them about tube 154 in bearings 156. Fingers 160 enter openings 39 in mold plate 42 as shown at station D in FIGURE 1. As this action is completed, bear off support 154 engages mold side switch 45 as shown in FIGURE 13. This sends impulse to valves in indexing cylinder 224 and mold side cylinder 256.

INDEX MECHANISM RETURN STROKE

In FIGURE 14, pressure reversal in cylinder 224 causes rod 226 to extend turning with it flanged bearing 228 and clutch 230. These turn freely, imparting no relative motion to drum 32 since clutch 230 has been de-energized for some time due to signal from station cycle starting switch 235 as set forth in operation of indexing mechanism.

MOLD ASSEMBLY OPERATION

Simultaneously with above as shown in FIGURE 5, mold side cylinders 256 extend rods 254 and rams 250 causing mold side 246 to enter into a back-up position with corner molds 52 which are already at station C. Filler blocks 244 have been removed of course, prior to starting the corner block making. Wing latches 247 have engaged locks 161 and 183 thereby holding pallet 164 and rear mold side 182 against any spreading force. At the same time, end of ram 250 engages lug 47 on plate 42 to hold corner molds 52 in place against compaction pressure.

At the end of extending stroke of mold side piston rod 254, trip bar 253, mounted on ram 250, engages core switch 251, sending impulse to integral valve in cylinder 208 and energizing circuit thru upper separator switches 195. In FIGURE 13, pressure reversal in core plate cylinder 208 causes rod 206 to extend, pushing core plate

184 with cores 192 into mold compartment. Upon energizing circuit of separator switch 195, any single or several switches 195 which have engaged key lugs 50 on mold 46 will correspondingly relay impulse to their particular separator cylinder or cylinders 190 actuating the integral valves therein. This pressure reversal then extends rod or rods 188 and separator or separators 180 thru guide bar 186, core plate 184, and rear mold side 182 into mold compartment in a position directly over lower separator or separators depending upon which mold 46 happens to be at that station at that time.

In FIGURE 1, at the end of core plate travel, trip bar 197 engages funnel strike-off switch 199 sending impulse to integral valve in funnel strike-off cylinder 174 causing piston rod 172 to extend, pushing funnel strike-off 166 outward over mold compartment, thereby depositing the excess mix, which remained from last cycle, into mold compartment.

In FIGURE 5, near the end of outward stroke of funnel strike-off 166 trip lug 167 mounted thereon actuates feeder motor starting switch 169 attached to guide 170 sending simultaneously, impulses to feeder motor starting switch 261, time controller 263, and oscillator control 265, shown in FIGURE 13. This starts feed motor and energizes compactor cylinders 290 causing compactors 284 to reciprocate up and down for a predetermined period. At the end of timed interval, feeder 258 stops, compactors 284 stop in an up position and impulse is sent by time control 263 to integral valve in funnel strike off cylinder 174 causing funnel strike off 166 to retract. This action strikes off excess material evenly and slightly above block top.

In FIGURE 13, at end of funnel strike off retraction stroke, trip 171 engages finishing plate switch 173 sending impulse to integral valve in finishing plate assembly cylinder 278 causing piston rod to extend, forcing yoke 276, assembly 270, and finishing plate 282 downward to size and finish blocks. Impulse from finish plate switch 173 is also directed to clutch valve 234 engaging clutch 230 to drum 32 in preparation for next indexing.

When correct block thickness is reached, trip 289 engages block thickness switch 291 causing finishing plate 282 to retract to starting position shown in FIGURES 5 and 13. Block thickness switch 291 also sends impulse to integral valves in core and separator cylinders 190 and 208 thereby retracting cores 192 and separators 180. In FIGURE 1, as core plate 184 reaches fully retracted position, trip bar 197 engages mold side retraction switch 179 sending impulse to mold side cylinders 256 shown in FIGURE 5 causing mold sides 246 to retract, which frees rear mold side 182 and bear-off cradle 158. In FIGURE 5, as ram 250 retracts it actuates core carriage retraction switch 273, sending impulse to integral valve in core carriage cylinder 214, shown in FIGURE 13, causing rod 212 to extend, pushing core carriage 178 back and clearing mold 46. Core carriage switch 273, in anticipation, also sounds gong advising operator blocks are ready to be borne off.

"BEAR-OFF" OPERATION

In performing this part of block production, operator, who has heard the anticipatory signal from machine, turns into proper position while unit is being completed. He then steps on left hand treadle 157L, which by lever action raises entire bear-off 154 including roll over cradle 158, pallet 164, finished product, mold corners 52, and mold 46, freeing the latter from positioner on plate 42. He then grasps cradle 158L and swings bear-off clear of machine. Next he places mold 46, which he removed from product during last bear-off, on machine at station C. Then he presses index button 165, shown in FIGURE 5, and proceeds to place another pallet 164 on right hand bear-off cradle 158 R. Upon gong sounding, completion of machine indexing is indicated and he swings right bear-off 158R with pallet 164 into machine which then proceeds

to complete the back-up operation for the next group of blocks.

While this back-up operation for the next group is in progress, operator rolls cradle 158L, as shown in FIGURE 5 by broken lines, completed block, pallet 164, mold 46, and mold corners 52, over. This new position of cradle 158L now has completed block resting on pallet 164, which operator now pulls with molds away from fingers 160. He next strips corner molds 52 from block and mold 46 and places them on a stand (not shown) between stations B and C for use, in turn, with other mold corners on subsequent blocks. Mold 46 is now stripped from block and placed on stand (not shown) and is also now ready for reuse.

Block now rests alone on pallet 164 which operator grasps and places both on a conventional block curing rack. Now he places an empty pallet 164 on cradle 158L, whereupon he has reached the point of operation identified as "bear-in" which has previously been set forth. The next "bear-off" operation will be identical to the one just described except it will be done with right "bear-off" which is now in machine having block completed.

POWER BRUSH DESCRIPTION

In FIGURE 1, cylindrically shaped brush 292 is securely attached to shaft of gear motor 294 which is rigidly mounted to frame 22 so that brush will engage all the top parts of mold 46 while it is moving from stations D to E. This is accomplished by making brush length enough longer than mold width to enable it to cover every part of mold 46. Extra brush length is necessary since the difference between the maximum and minimum radii from center of shaft 28 to the various mold extremities is greater than mold width itself. Brush motor start control 293 is mounted to frame 22.

POWER BRUSH OPERATION

At an electrical signal from indexing switch 165, brush motor start control 293 is energized, motor 294 starts, and brush 292 revolves. Rotation of brush continues until the set of normally closed contacts in trigger switch 235, FIGURE 14, are opened. Mold 46, during this interval, has started from station D, traversed completely under the revolving brush, and stopped at station E with all residue from previous cycle loosened therefrom.

AIR JET DESCRIPTION

In FIGURE 1, a conduit 296, having openings therein, is operably mounted to frame 22, so that air emerging from openings would be directed in a plane at the position between stations E and F and slightly above elevation of top of mold 46. Conduit 296 has valve 298 operably connected thereto for controlling flow of air, and is further connected to an outside source of air pressure.

AIR JET OPERATION

Electrical impulse from switch 165 at start of indexing operation, actuates valve 298 causing air under pressure to flow thru conduit 296 and out openings therein. This blows loosened mix residue clear of mold 46 which is passing beneath. At end of indexing operation, impulse from trigger switch 235 operates valve to stop flow of air.

MIST SPRAY DESCRIPTION

Rigidly mounted to frame 22 between stations F and A and slightly above elevation of top of mold 46, is spray nozzle 300, as illustrated in FIGURE 1. A dual conduit 301 connects nozzle 300, to a valve, an outside source of lubricant, and to an outside source of air pressure.

MIST SPRAY OPERATION

An electrical impulse from switch 165 at start of indexing operation actuates valve 302 which causes mist of lubricant to be directed at mold 46 which is now passing beneath nozzle. As indexing cycle is completed, trigger

13

switch 235 sends electrical impulse to valve 302 which stops flow of air and lubricant.

GENERAL

The machine will be further equipped with sufficient conventional safety limit switches which prevent, for example, the indexing mechanism from functioning until all the various components at stations A, B, and C are in their fully retracted positions and are clear of molds 46 and attendant supports. These are not shown as this is a usual precaution taken on most automatic machinery. Separators 180 and cores 192, do not move with core carriage and rear mold side for the following reasons. First there must be an initial movement of carriage with switches to engage mold keys to determine which separators shall advance. Second, cores and separators should not contact pallet 164 prior to it being locked in place with rear mold side 182. Extra facing mix could cause cores to force pallet and bear off away from mold. And third, rear mold side must support block while cores and separators are withdrawn to avoid damage to block.

I claim:

1. A block machine having a frame and a movable table secured to said frame, a pressure cylinder secured to said frame and having a reciprocable piston and rod; a source of fluid under pressure; conduits for directing fluid under pressure between said source and said pressure cylinder to reciprocate the piston and rod of said pressure cylinder selectively; a clutch, one portion of which is attached to the piston rod of said cylinder and the other member of which is secured to said movable table; a valve secured to said pressure cylinder and interposed in said conduits between said source and said pressure cylinder; an operating arm secured to said valve; means secured to said piston rod and operatively engaging said valve operating arm to open said valve during the middle portions of each reciprocation of said piston rod and at least partially close said valve at the ends of each reciprocation; and means for engaging said clutch before said pressure cylinder piston rod is actuated in one direction of reciprocation and for releasing said clutch before said pressure cylinder piston rod is actuated in the other direction of its reciprocation.

2. The block machine of claim 1 in which the means for opening and closing said valve during reciprocation of said piston rod comprises, a cam follower secured to said valve arm, and a cam secured to said piston rod of said pressure cylinder and engaging said cam follower.

3. The block machine of claim 1 in which said movable portion has face molds thereon; mold sides movably secured to said stationary portion and alternately movable into and out of engagement with said face molds successively; means secured to said stationary portion above said mold sides and a face mold when said movable table is stopped for placing molding material on said face molds when engaged by said mold sides; and means for withdrawing said mold sides before said movable portion is indexed.

4. The block machine of claim 3 in which the means for opening and closing said valve during reciprocation comprises an arm operably secured to said valve, a cam follower on the end of said arm, and a cam secured to the piston rod of said pressure cylinder and engaging said cam follower.

5. The block machine of claim 4 in which latches are secured to said movable portion; a latch seat movably secured to said stationary portion; and means for moving said latch seat into engagement with one of said latches after indexing is completed and withdrawing said latch seat before indexing starts selectively; said latches and latch seat being a wedge and V-shaped, respectively.

6. The block machine of claim 5 in which some of said face molds have separator portions thereon; key lugs secured to said face molds having separator portions thereon in alignment therewith; movable separators se-

14

cured to said stationary portion; means on the stationary portion of said machine for moving said movable separators selectively into and out of engagement with a mold; means aligned with said movable separators on said stationary portion and when engaging said key lugs initiating movement of said movable separators into a face mold; said movable separators otherwise remaining stationary.

7. The block machine of claim 1 in which there are at least two face molds secured to said movable portion; a separator portion in one of said face molds; a key lug secured to said one face mold in alignment with said separator portion; a set of mold sides movably mounted on said stationary portion; means secured to said stationary portion and said mold sides for moving them into and out of operable engagement with said face molds at times; at least one movable separator secured to said stationary portion; means for moving said movable separator into and out of operable engagement with said mold sides; and means aligned with said movable separator and secured to said stationary portion and when engaging said key lug, initiating movement of said movable separator into operable engagement with said mold sides; said movable separator being withheld from movement when said means aligned with said separator engages no key lug.

8. The block machine of claim 1 in which latches are secured to said movable portion; a latch seat movably secured to said stationary portion; and means for moving said latch seat into engagement with one of said latches after indexing is completed and withdrawing said latch seat before indexing starts selectively; said latches and latch seat being a wedge and V-shaped, respectively.

9. A block machine comprising a frame; at least two face molds secured to said frame; a separator portion on one of said face molds; a key lug secured to said one face mold in alignment with said separator portion; a set of mold sides movably mounted on said frame; means secured to said frame and said mold sides for moving them into and out of operable engagement with said face molds; at least one movable separator secured to said frame; means for moving movable separator into and out of operable engagement with said mold sides; and means aligned with said movable separator and secured to said frame and when engaging said key lug, initiating movement of said movable separator into operable engagement with said mold sides; said movable separator being withheld from movement when said means aligned with said movable separator engages no key lug.

10. The block machine of claim 9 in which said machine is a dual mix block machine; said movable separator moves horizontally; cores movably secured to said frame adjacent said mold sides; means secured to said frame for moving said cores into and out of said mold sides in paths parallel to said movable separator; a bear off structure vertically pivoted to said frame near one end of said mold sides and including roll-over structure horizontally pivoted to pivot only ninety degrees.

11. In a machine having a frame and a movable table secured to said frame, the improvement comprising; a pressure cylinder having a piston and rod; said pressure cylinder being secured to said frame; the piston rod of said pressure cylinder being secured to said movable table; a source of fluid under pressure; conduits extending between said source and said pressure cylinder for reciprocating said pressure cylinder piston and rod selectively; a valve secured to said pressure cylinder and interposed in said conduits; said valve having an operating arm; means secured to said piston rod and operatively engaged with said valve operating arm to open said valve during the middle portion of each reciprocation of said piston and rod and at least partially closing said valve during the terminal portions of each reciprocation of said piston and rod.
